UNITED STATES PATENT OFFICE.

JAMES COOKE, OF OMAHA, NEBRASKA.

LABEL HOLDER.

Application filed November 4, 1921. Serial No. 512,814.

To all whom it may concern:

Be it known that I, JAMES COOKE, a citizen of the United States, and a resident of Omaha, in the county of Douglas and State 5 of Nebraska, have invented certain new and useful Improvements in Label Holders, of which the following is a specification.

My invention relates to label holding devices adapted for attachment to articles of 10 wood or like material into which fastening means may be driven to secure the label-holder thereon. It is the object of my invention to provide a label-holder of this character, which may be economically produced 15 from thin soft sheet-metal, the holder being formed by drawing or rolling a flat strip of the sheet material, and being produced in long pieces from which sections of the desired length may be cut as required 20 for use. A further object of my invention is to provide, integrally with the body of the holder, means for securely and permanently attaching the same to the article on which it is to be used, the attaching 25 means comprising tongues turned out from the body and adapted to turn laterally and clinch in the material into which they are driven. A further object of my invention is to produce, in the attaching-tongues 30 formed from the soft material, such hardness, strength and rigidity as to fully adapt the same for driving into hard wood, without liability of the tongues bending laterally prior to the entry thereof into the 35 wood, and thus failing to enter the wood, clinch therein, and securely retain the holder in position thereon.

In the accompanying drawings Fig. 1 is a front view of a strip of the formed 40 material from which the label-holding sections are made, the central portions of the strip being broken away, Fig. 2 is an end view of the same, Fig. 3 is a front view of a label holder formed from the strip and attached to a support, Fig. 4 is a longitudinal section, on a greatly enlarged scale, through a portion of the holder, the section being in the plane of the line 4—4 of Fig. 3, and Fig. 45 5 is a detail sectional view, showing the preferred method of forming the attaching-tongues.

The label-holder provided by my invention comprises a flat body or plate 6 of soft sheet-metal, having at uniform intervals 50 throughout its length annular series of pointed tongues 7 turned back from the

body of the plate so as to extend perpendicularly to the plane thereof, and having along its longitudinal edges continuous flanges 8 which are turned forwardly 60 and inwardly from said edges of the body-plate. Said flanges 8 provide parallel opposed U-shaped channels, between which a label of stiff paper, cardboard or the like 65 may be inserted, either by sliding the label in longitudinally from the end of the holder, or by inserting one edge of the label into the channel at one side of the holder, then bowing the label transversely sufficiently to enable insertion of the opposite edge in the 70 other channel, and finally flattening down the label against the body-plate to complete the entry of its edges beneath the in-turned edges of the flanges.

The holders are preferably produced in 75 as long pieces as may be conveniently handled, and sections of the desired length cut from such long pieces as required for use. The user may thus secure holders of 80 any desired length without the necessity of keeping in stock all of the various lengths that might be desired. The material used in the holders is preferably soft sheet-metal, such as soft brass, or soft iron suitably coated, as with tin, nickel, lacquer or 85 like material, to prevent corrosion. Thin material is used in order that a minimum weight thereof may be required, and also to facilitate the drawing or rolling of the same to form the flanges 8 at the edges of 90 the strip. The drawing or rolling of the flanges is also facilitated by the use of a soft rather than a hard material. The use of a 95 soft material also facilitates the cutting of the shorter sections from the long pieces, and enables the user to readily flatten down 100 the inturned flanges so as to grip the edges of the label, should it be desired to permanently secure the label in the holder. Accidental displacement of the label, by movement longitudinally of the holder, may also 105 be prevented by crimping down the flanges 8 at the ends thereof, as clearly shown at 9 in Fig. 4. The crimped portions 9 at the ends of the flanges may be conveniently produced by inserting the label into a portion 110 of the long strip, and then cutting from said strip the portion containing the label, by means of ordinary shears, which will press down the flanges simultaneously with the cutting of the same.

The tongues 7 are formed from circular

portions of the body-plate 6, at uniform intervals throughout its length, each of said circular portions of the plate producing an annular series of the tongues, which are originally sectors of the circular portion, and which remain attached to the plate at the border of the circular opening formed by their displacement from the original plane. Each tongue is thus of approximately triangular form, having a sharp point directed outwardly from the plate, the opposite or base portion being attached to the plate, and the body of the tongue being transversely curved. The preferred means for forming the tongues are represented in Fig. 5, and comprise a die A having a cylindrical opening through it, and a cylindrical punch B having a pointed end-portion formed by a number of symmetrical plane-surfaced facets C. The diameter of the punch-body is such that when it is inserted in the opening through the die the clearance between its cylindrical body and the walls of the opening will be slightly less than the thickness of the material in the plate 6. After the drawing or rolling of the strip to form the flanges 8, the back of the strip is placed upon the upper surface of the die, and the punch is actuated by suitable means to drive the same through the plate and into the die, or to a position substantially as shown in Fig. 5. As the point of the punch engages the plate 6, the material therein is cut or broken along the radial lines determined by the corners at the junctures of the facets C, and as the downward movement of the punch is continued the tongues are turned downwardly and bent, drawn and swaged to their completed form. On account of the clearance between the punch and die being less than the normal thickness of the sheet material, the material in the tongues is slightly drawn and swaged, so that the tongues are slightly longer than they would be if they were merely bent outwardly from the body of the plate without being confined between the punch and die. The resultant lengthening of the tongues, by the swaging thereof, is advantageous not only in that the tongues are adapted thereby to penetrate more deeply into the wood or other support to which the holder is attached, but also in that the soft material is hardened and stiffened by the swaging and drawing thereof, so that the tongues are not too easily bent or crumpled during the driving thereof into the support. The tongues are further strengthened against bending or crumpling thereof, by reason of their transverse curvature, and, obviously, the latter is more effective at the wide ends or bases than at the points, since the arc near the points is so slight as to be inappreciable. As a further result of the manner in which the tongues

are formed, their edges are slightly beveled at the points 10 thereof, so that when the tongues are driven into the wood support for the holder there is a tendency for the end-portions of the tongues to curl or form hooked portions 11, as represented in Fig. 4. The tendency of the tongues to curl or clinch in the wood is especially marked when they enter the wood parallel with the grain thereof, and, by reason of the annular arrangement of each set or series of the tongues, two or more of the same are always so situated as to extend approximately parallel with the grain of the wood. The tongues which extend transversely to the grain of the wood will usually clinch therein, but are not so certain to do so as those which are parallel with the grain. In actual practice it is found that when the described holder is placed upon a hard wood support, such as indicated at W in Fig. 3, and forcibly pressed thereagainst, as by a hammer blow, the tongues will readily penetrate the wood and nearly all of the same will curl or clinch therein. The holder is thus secured to the support permanently, or so that it can be displaced only by the application thereto of a substantially destructive force.

It will be seen that the described label-holder may be readily and economically produced, and that it is applicable for use under a great variety of conditions, as for securing labels to cabinet drawers, wood shelving, boxes, directory boards, and the like.

Now, having described my invention, what I claim and desire to secure by Letters Patent is:

1. A label holder comprising a body plate of soft sheet metal bent at the side edges to form label receiving flanges and provided between the flanges with a series of transversely curved swage-hardened tongues formed integral with the body plate and extending perpendicularly thereto, said tongues having pointed ends and wide base portions, the latter joining the body plate, said hardened tongues being adapted for driving into an imperforate support, to secure the label holder to the face of the same.

2. A label holder comprising a body plate of soft sheet metal bent at the side edges to form label receiving flanges and provided with an annular series of transversely curved swage-hardened tongues formed integral with the plate and extending perpendicularly thereto, said tongues having pointed ends and wide base portions and the edges of the tongues adjacent to their points being bevelled whereby to direct said tongues laterally when penetrating a support and thereby effect automatic clinching of the tongues therein.

3. In an article of manufacture, a relatively long body strip of soft sheet metal having opposite U-shaped label receiving flanges at its longitudinal edges and adapted to be cut into required lengths to form label holders and series of substantially triangular tongues extending perpendicularly from the said strip between the flanges thereof at intervals, the bases of said triangular tongues joining the strip and the tongues being transversely curved on a short radius whereby to stiffen and adapt the same for hammering into an imperforate support and the edges of the tongues adjacent to their points being bevelled whereby to direct said points laterally when penetrating a support and thereby effect automatic clinching of the tongues therein. ¹⁵
